SOLENOID

Dean W. Davis, Oak Park, Ill.

Application August 18, 1941, Serial No. 407,311

3 Claims. (Cl. 175—341)

This invention relates generally to an electromagnetic device and in particular to a solenoid having a magnetic frame with an operating armature or plunger movable in and out of such frame.

It is an object of this invention to provide a solenoid of improved construction.

Another object of this invention is to provide a solenoid in which the guideway for the movable plunger extends over the entire length of the magnet frame to provide for a linear movement of the plunger at all operating positions thereof. Freezing of the plunger with the magnet frame at any operating position is thus entirely eliminated.

A further object of this invention is to provide a solenoid which is of simple and rugged construction, and comprised of a minimum number of parts which are simply and quickly assembled and disassembled for manufacturing and servicing purposes.

A particular feature of this invention is found in the provision of a solenoid in which the guideway for the operating plunger is integrally formed with a fastening portion at one end adapted to be bent over in engagement with a corresponding portion of the magnetic frame, with the resulting hooked engagement of the fastening portion with the frame constituting the sole means for securing the guideway to the frame.

Another feature of this invention is found in the provision of a guideway for the operating plunger which is retained in the magnetic frame substantially entirely within the confines thereof, and without the use of any special fastening means such as rivets, screws, or the like.

Further objects, features and advantages of this invention will become apparent from the following description when taken in connection with the accompanying drawing in which:

Fig. 1 is a front perspective view of the improved solenoid of this invention;

Fig. 2 is a sectional view taken along the line 2—2 in Fig. 1 illustrating the manner of assembling the plunger guideway in the magnetic frame;

Fig. 3 is a perspective view of one of the guideway channel members;

Fig. 4 is a view partly in section of a modified form of the invention; and

Fig. 5 is a fragmentary sectional view as seen along the line 5—5 in Fig. 4.

In the practice of this invention there is provided a solenoid having a C-shaped magnetic

frame with a plunger movable in and out of the frame through the opening at the one end thereof. A bracket for mounting the solenoid is positioned over each side of the frame and is formed with outwardly extending U-shaped portions at each frame end which are in substantial alignment with the frame opening longitudinally of the frame. A guideway for the operating plunger is comprised of a channel member at each side 5 of the frame, with each channel member being adapted to be received within the U-shaped portions of a corresponding bracket member, and of a construction providing for its rigid assembly with the frame and bracket member without 10 requiring special fastening means such as rivets, holding pins, or the like.

Referring to the drawing the solenoid of this invention is illustrated in Figs. 1 and 2 as including a magnetic frame 10 of C-shape comprised of laminations 11 held together by rivets 12. The mounting brackets or strap means for the solenoid include a one-piece stamped bracket 13, on each side of the frame 10, of substantially right-angle shape and having a base portion 14 and a side portion 16. The side portion 16 is provided with a central opening for receiving an operating coil 17 therethrough, and is of a form to completely cover a corresponding side of the frame 10. The rivets 12 are utilized to secure the mounting brackets to the frame 10, the laminations 11 being clamped between the bracket as is clearly shown in Fig. 1. Each bracket 13, at the ends of the frame 10, is formed with outwardly bent U-shaped portions 18 and 18a which are in substantial alignment longitudinally of the frame with the opening 19 therein. The base section 21 of each bent portion 18 is provided with an aperture 22 to be later noted.

The operating armature or plunger 23 for the solenoid is movable in and out of the frame 10 through the opening 19 and is shown in Fig. 1 as being comprised of laminations 24 and side plates 26 greater in length than the laminations 24 and extending outwardly from each end of the frame 10. The side plates 26 and laminations 24 are secured together in a well-known manner as by rivets or the like (not shown). Coupling members 27 are positioned between the corresponding ends of the side plates 26 for connecting the plunger 23 to the particular apparatus with which the solenoid is employed. The plunger 23 is guidably supported for linear travel in a guideway indicated generally as 28 (Fig. 2) and including a pair of non-magnetic members 29 of a channel shape over their entire length.

Each channel member 29 is formed at one end with an extending or nose portion 31, the channel legs 32 at the portion 31 being of a reduced height and of a bevel shape which converges from the extreme end of the portion 31 inwardly of the channel member for a purpose to be explained later. The other end 33 of each channel member is formed with a bumped-out lug or fastening portion 34, which, before the assembly of the member 29 in the solenoid, projects outwardly from the channel base 36 as shown for the top channel member 29 in Fig. 2, and as illustrated in Fig. 3.

In assembling the solenoid the coil 17 is positioned within the frame 10 and a channel member 29 is passed through the frame opening 10 and through the center of the coil 17 with the nose portion 31 arranged at the opening or cavity 37 formed between the laminations 11 and a portion 18a of a corresponding strap member 18. As previously mentioned, the lug 34 projects outwardly from the base portion 36 so that a channel member at this position of its assembly is inclined relatively to the strap portion 16 by virtue of the lug 34 being arranged between the portion 16 and the channel member. However, the bevel on the nose portion 31 provides for the easy insertion of the nose entirely within the cavity 37 while the member 29 is thus inclined, the position of the lug 34 on the channel member being such that after the extension 31 is in the opening 37 it is disposed opposite the aperture 22 in the bracket portion 21, as shown in Fig. 2 for the top one of the channel members. When the channel member 29 is in this position, the end 33 thereof is pivoted about the end 31 until the base portion 36 is in parallel alignment with the strap portion 16, the lug or fastening portion 34 during this pivotal movement being inserted into the aperture 22 of a bent portion 18. The fastening portion 34 is then bent or hooked over against the outside of the base section 21 of the bent portion 18 as shown in Figs. 1 and 2 to retain the channel member fixed on the frame 10.

From a consideration of Fig. 2, it is seen that the wide or extreme end of the nose portion 31 extends completely transversely across the opening 37 so as to be in frictional engagement with the bracket 18 and laminations 11 when the channel member is in its assembled position. This frictional engagement rigidly holds the channel end 31 against any movement relative to the bracket 18 after the hooked engagement of the fastening portion 34 with the bracket 18. The central opening 38 in the operating coil 17 is of a size such that a slight pressure is applied on the coil by the channel member during its pivotal movement from the top position shown in Fig. 2, to its lower position shown in the same figure. The coil and channel members are thus in frictional engagement so that the coil is secured in a fixed position in the frame 10 concurrently with the fastening of the channel members in their assembled positions. The plunger guideway 28 is thus secured to the frame 10 solely by the hooked engagement of the lug portions 34 with corresponding brackets 18 so that any special fastening means, such as rivets or the like, is entirely eliminated.

Since the channel members 29 are of a length substantially equal to the longitudinal length of the frame 10, and are of a channel shape over their entire length, the plunger 23 is guidably supported throughout its travel in the frame. Any tilting of the plunger 23 from the path of

linear movement and consequent possible freezing of the plunger with the frame is thus eliminated for all operating positions of the plunger. In the assembly of the solenoid, therefore, all 5 of the parts thereof are relatively fixed on bending over of the guideway fastening portions 34. When the solenoid is to be serviced, as for instance to replace the operating coil, the solenoid is quickly dismantled by straightening or unbending the lugs 34 and withdrawing such lugs 10 out of engagement with the frame strap members 18.

It is evident from a consideration of Fig. 2 that the width of the nose portion 31 of a channel member and the extension of the U-shaped portions 18 and 18a outwardly of the brackets 18 is dependent upon the provision of a proper operating clearance for the side plates 26 of the plunger 23 between the brackets and laminations 11. In the modified form of the invention in Figs. 4 and 5, there is illustrated a solenoid with a frame 10 and an operating coil 17 having a plunger 23' in which a coupling member 27 is assembled at only one end thereof, the plunger being movable through the frame opening 10' outwardly from the frame end or wall 41. The side plates 26' of the plunger extend outwardly only at the coupling end of the plunger, with the innermost position of the plunger being defined by the back frame wall or end 42. Since the plunger does not travel beyond the frame end 42 no operating clearance therefor is required between the laminations 11 and the U-shaped portions 43a at the frame end 42. The cavity 37' between the laminations 11 and the bent portions 43a may thus be appreciably reduced relative to the cavity 37 shown in Fig. 2 to a size adapted to provide sufficient space to receive only a channel member 29'.

40 Thus as shown in Fig. 5 the extreme end of the nose 31' is of a width slightly greater than the thickness of the channel base portion 36' to provide for a bevel shape of the nose for assembly purposes. The U-shaped portion 43a of the bracket member 18' is correspondingly reduced in size and is bent outwardly only enough to accommodate the nose portion 31'. The channel member 23' apart from the construction of the nose end thereof is similar in all other respects to the channel members 29 fully described above. The assembly of the channel member 23' in the solenoid is also similar to the assembly of the corresponding channel members 29 and is believed to be entirely clear from the 45 showing in Fig. 5, so that a further description thereof is believed to be unnecessary.

From a consideration of the above description and drawing, therefore, the invention is seen to provide a solenoid in which the guideway for the 50 operating plunger is of a construction providing for its self-assembly in the solenoid without requiring separate fastening or securing means. This construction provides for the guideway being substantially entirely within the confines of the 55 solenoid frame so that the solenoid is compact and neat in appearance. By virtue of the guideway being rigidly held in a fixed position by a frictional engagement at one end with the frame laminations 11 and strap members 18, and at its 60 other end by a hooked engagement of an integral part thereof with the strap members, the assembly and disassembly of the solenoid is greatly simplified while providing for a guideway which 65 functions to positively support the operating 70

plunger for linear movement over its entire path of travel.

Although the invention has been described with specific reference to several preferred forms thereof it is to be understood that it is not to be so limited since the parts and their arrangement can be changed therein within the full intended scope of the invention as defined by the appended claims.

I claim:

1. A solenoid having a plunger and a frame with spaced-apart portions with each portion having a recess therein, the means for supporting the plunger for movement in a straight line path in the solenoid, including a pair of one-piece guide members, each of said members having an extension at one end including two parallel sides each cut away angularly longitudinally thereof to provide a reduced width in a portion thereof and a connecting body portion at right angles to the sides, and an integral lug at the other end of each member, said extension being positioned in one of said recesses, and with said side construction permitting the original insertion of said extension therein in a direction other than a straight-line direction parallel to the plunger path of movement, and with an opposite frame portion recess having an aperture in a wall thereof, with said other end positioned in said other recess and said lug having a portion in said frame wall aperture and another portion on the outside of said other frame portion, said member being fixedly maintained at said ends in said recesses without any fastening means other than said lug in said aperture.

2. A solenoid having a plunger and a frame with oppositely disposed recesses therein on each side of the frame and a wall portion on the outside of each recess with an aperture in one recess wall on each side, the means for supporting the plunger in a straight-line path of movement including a pair of one-piece guide members, each of said members having an extension at one end with side walls which are wider at one end than the other, and having an integral lug at the other end, said side walls and said lug being so shaped and located as to permit insert-

ing said extended end into one recess on one side of the frame during assembly of the solenoid, with the lug in upstanding condition in a direction other than parallel to the direction of plunger movement, and then turning the member to locate its other end in the other recess on the same side of the frame and extend the lug outwardly thru the aperture in the wall of the latter recess, said lug having a part extending outwardly from said recess through said aperture and another part extending away from said aperture substantially against the outer face of the wall portion.

3. A solenoid having a magnetic frame with a plunger movable in and out of said frame, a part secured to each side of said frame, each part having an outwardly formed-portion at each end of said frame, and with the formed-portion at one frame end having an aperture in the wall thereof, the means for guiding said plunger in said frame including a channel member at each side of said frame, each channel member having a longitudinal extension at one end with a projecting portion thereon positioned within a corresponding formed-portion with the extension including the projecting portion in firm frictional engagement with a wall of said formed-portion and a wall of said frame, and an integral lug portion near the other end of the channel member, with said other end positioned within the corresponding formed-portion at that frame end and said lug portion extending from the channel member outwardly through the aperture of the corresponding formed-portion, and having a part upset against the outer face of that formed-portion, each channel member being positioned with its opposite ends within the corresponding formed-portions and fixedly retained in the solenoid by the lug portion connection with the formed-portion aperture and by the firm frictional engagement of the extension including the projecting portion with the inside wall of the corresponding formed-portion and the oppositely disposed wall of the magnetic frame.

DEAN W. DAVIS.
